DECORATIVE COVER OR SIMILAR ARTICLE

William Shiner, 4815 14th Ave.,
Brooklyn, N.Y. 11219

Filed Feb. 1, 1967, Ser. No. 5,645

Term of patent 14 years

(Cl. D97—1)

Fig. 1

Fig. 3

FIG. 1 is a front perspective view of a decorative cover or similar article embodying the ornamental features of my design and showing my design with the cover in open position;

FIG. 2 is a front plan view showing my design with the cover in closed position;

FIG. 3 is an enlarged sectional view taken along line 3-3 of FIG. 1;

FIG. 4 is an enlarged fragmentary elevational view as seen in the direction of line 4-4 of FIG. 3.

I claim:

The ornamental design for a decorative cover or similar article, as shown and described.
